UNITED STATES PATENT OFFICE.

WILLIE L. DAUGHRAY, OF MULBERRY, FLORIDA.

SHAFT-BRACE.

1,073,476.

Specification of Letters Patent. Patented Sept. 16, 1913.

Application filed May 19, 1911. Serial No. 628,244.

To all whom it may concern:

Be it known that I, WILLIE L. DAUGHRAY, a citizen of the United States, residing at Mulberry, in the county of Polk and State 5 of Florida, have invented a new and useful Shaft-Brace, of which the following is a specification.

This invention relates to braces for use in connection with shafts or thills, the object of the invention being to provide a light but durable brace which can be readily applied to ordinary types of thills and which holds the thills fixed relative to the cross bar and prevents distortion thereof.

Another object is to provide a device of this type which also serves as a means for securely attaching the cross bar to the thill.

With the foregoing and other objects in view which will appear as the description 20 proceeds, the invention resides in the combination and arrangement of parts and in the details of construction hereinafter described and claimed, it being understood that changes in the precise embodiment of the invention herein disclosed can be made within 25 the scope of what is claimed, without departing from the spirit of the invention.

In the accompanying drawings the preferred form of the invention has been 30 shown.

In said drawings:—Figure 1 is a plan view of the brace, portions of a thill and cross bar being shown. Fig. 2 is an end elevation of the brace, a thill being shown in 35 section and a portion of the cross bar being shown in elevation. Fig. 3 is a section on line A—B Fig. 1.

Referring to the figures by characters of reference 1 designates a web adapted to be 40 fitted against the inner face of a thill C and into the angle formed by the thill and the cross bar D. Another web 2 is extended from the web 1 and is integral therewith, this web 2 being mounted on the front face 45 of the cross bar D and extending up to the thill C. A diagonally disposed brace strip 3 connects the outer end portions of the two webs and is formed integral with them. Web 1 has upper and lower parallel flanges 50 4 extending laterally therefrom and adapt-

ed to receive the thill C between them. These flanges extend rearwardly beyond the web 1 and also a short distance forwardly therefrom, the rearwardly projecting portions 5 of the flanges being curved so as 55 to conform with the curvature of the thill C. Upper and lower flanges 6 extend rearwardly from the web 2 and are formed integral with the flanges 5, these flanges 6 being adapted to bear upon the upper and 60 lower faces of the cross bar D and being extended beyond the free end of the web 2. The flanges 4 and their extensions 5, as well as the flanges 6 are formed with openings 7 for the reception of rivets or other 65 fastening means whereby the device is securely fastened to the thill and cross bar and serves not only to hold them together but to prevent movement of either of them relative to the other.

While the device has been shown applied to shafts, it is to be understood that it can also be employed as a brace in connection with poles.

What is claimed is:—

As an article of manufacture, a brace for shafts, said brace including angularly disposed integral webs, a diagonal brace integral with and connecting the free end portions of the web, flanges integral with and 80 extending longitudinally along the upper and lower edge portions of one of the webs, rearwardly extending flanges upon the upper and lower flanges of the other web and integral with the first named flanges, and 85 rearwardly projecting extensions integral with the first named flanges, said extensions and the upper and lower flanges being spaced apart to slide onto a thill, and said rearwardly extending flanges being spaced 90 apart to slide onto a cross bar, said flanges and extensions having fastener receiving openings.

In testimony that I claim the foregoing as my own, I have hereto affixed my signature 95 in the presence of two witnesses.

WILLIE L. DAUGHRAY.
